UNITED STATES PATENT OFFICE

HERBERT HENRY BAKER, OF MONKSEATON, NORTHUMBERLAND, AND CHRISTOPHER SAMUEL DAVY, OF DULWICH, LONDON, ENGLAND, ASSIGNEES TO THE BABCOCK & WILCOX COMPANY, OF BAYONNE, NEW JERSEY, A CORPORATION OF NEW JERSEY

DISTRIBUTING MEANS FOR FUEL TO STOKERS

Application filed October 30, 1919, Serial No. 334,508, and in Great Britain November 27, 1918.

The invention relates to improved means for uniformly distributing the fuel on to the grate surface of a mechanical stoker and has for its object to ensure that the dust and larger pieces of fuel as delivered from the bunker shall be thoroughly mixed and equally distributed across the grate surface of the stoker.

10 The invention consists broadly in the provision of means whereby the lower end of a chute leading to the stoker is caused to travel back and forth transversely of the direction in which the fuel is fed by the stoker.

In the accompanying drawings, Fig. 1 is a 15 side elevation partially in section, and Fig. 2 an end elevation of an arrangement according to the invention.

In the embodiment of the invention illustrated, there is mounted above the stoker hopper 1 a rotary cylinder or drum 2 formed with 20 a cam track constituted by two helical grooves 3 of opposite hand adapted to be entered by a follower constituted, for example, by a snug on a nut-forming element 4 which is attached 25 to the lower end of the hanging chute 5 supplying fuel from the bunker 6 to the hopper 1, and which in the rotation of the cylinder or drum 2 is caused to reciprocate axially thereof.

30 The cylinder or drum 2 may be driven by chain-gearing or otherwise from a revolving shaft, such as the sprocket shaft at the front of the stoker, if of the chain grate type, or from a separate shaft. In the embodiment shown, the cylinder or drum 2 is driven from the shaft 7 of the stoker mechanism A.

It will be evident that as the cylinder or drum 2 rotates, the lower end of the chute 5 will travel across the stoker hopper 1, and 40 upon reaching the end of its travel in one direction, will travel the same distance in the opposite direction, the reciprocatory movement being continuous, so that the dust and larger pieces of fuel discharged from the 45 chute will be well distributed in the stoker hopper.

What we claim and desire to secure by Letters Patent of the United States is:—

1. In combination, a mechanical stoker having a grate, a hopper extending crosswise of

the grate, a chute for conveying fuel to the hopper, and operating means connected to the chute and constructed and arranged to move the lower end of the chute back and forth lengthwise of the hopper, whereby a substantially uniform distribution of the fuel in said hopper is effected.

2. In combination, a chain grate stoker, a hopper located above the front end of said stoker and extending across the same to deliver fuel therefrom to said stoker, a chute for conveying fuel to the hopper, and operating means connected to said chute and constructed and arranged to move the lower end of the chute back and forth lengthwise of said hopper, whereby a substantially uniform distribution of the fuel in said hopper is effected.

3. In combination, a mechanical stoker and means for operating the same, a chute for conveying fuel to the stoker, an operating shaft, driving connections between said shaft and the stoker, and means associated with said shaft to move the lower end of said chute back and forth transversely of the direction in which the fuel is fed by said stoker.

4. In combination with an automatic stoker having a hopper, a swinging coal-feeding chute for feeding coal into and distributing it along said hopper, a member movable along said hopper, said member being connected to said chute, a rotatable shaft, driving means for rotating said shaft constantly in one direction, and periodically reversible power-transmission mechanism operatively interconnecting said shaft and said member to cause reciprocation of said member and chute along the hopper.
